UNITED STATES PATENT OFFICE.

EDWARD S. PEAKE, OF WESTERVILLE, OHIO, ASSIGNOR TO THE KILGORE MFG. COMPANY, OF WESTERVILLE, OHIO, A CORPORATION OF OHIO.

TOY PISTOL.

Application filed August 18, 1924. Serial No. 732,752.

The present invention relates to toy firearms of the type comprising means for feeding automatically a strip of caps and means for successively exploding the caps.

5 The invention has as its object the provision of an improved feeding mechanism for the cap strips and seeks to insure an even pressure of the feeding pawl upon the strip as the latter is moved toward the anvil.

10 A further object of the invention is to provide an improved feeding plate and anvil construction which will satisfactorily cooperate with the means for engaging and moving the cap strips across the feeding plate.

15 Another object of the invention is to provide a feeding plate construction which will permit an increased feeding movement of the cap strip without lengthening the stroke of the feeding pawl.

In the accompanying drawings there is shown one embodiment of the invention, and in these drawings

20 Figure 1 is a side elevational view with a portion of the casing broken away.

25 Figure 2 is a view similar to Figure 1 showing the position of the parts during the initial stages of the feeding operation, and

30 Figure 3 is a view similar to Figure 2 showing the relative positions of the parts at the completion of the feeding operation and just before the hammer is released.

35 In the drawings the invention is shown as embodied in a toy pistol which comprises the usual casing provided with a barrel 10 and a grip or stock 11. The operating mechanism includes a trigger 13 mounted upon a fulcrum pin 14 and having a rearwardly extending portion 15, upon which is pivotally mounted a feeding pawl 16 provided with a toe 15'. The feeding pawl is pivoted upon a stud 17 and is moved in a counterclockwise direction or forwardly by means of a spring 18 coiled about the stud 17 and having its 40 terminals engaging the pawl and trigger extension respectively. The trigger also carries upon a stud 19 a link 20 which engages a hammer 21 when the trigger is actuated and serves to retract the same. The hammer 45 is normally moved to the position shown in Figure 1 by means of a spring 22; and engagement between the hammer and the link is maintained by means of a spring 23 coiled about the stud 19 and extended to engage the 50 link and trigger respectively. The mecha-

nism above described is old and well known in the art and does not of itself constitute part of the present invention, it having been described merely for the purpose of making the application of the invention entirely clear.

55 The hammer engages an anvil 24 which is formed upon one of the casing sections and is extended downwardly to provide a cap strip feeding plate 24'. The plate forms a 60 compartment 25 for a cap strip roll 26 which may be mounted upon a supporting pin 27. The cap strip is lead rearwardly and upwardly from the face of the feeding plate, and, as will be understood, as the hammer is 65 retracted, the pawl 16 engages the strip and feeds the same upwardly. As the trigger is retracted, the pawl is moved toward the plate against which it is held by means of the spring 18. In the use of pistols of this 70 character it has been found that as the pawl is moved across the face of the anvil, there is a tendency, due to the gradually increasing tension of the spring 17, to tear and mutilate the cap strip. It is, therefore, desir- 75 able to make an allowance for this increase in tension and to maintain the pressure of the pawl upon the cap strip substantially even or uniform during the entire feeding operation. For this purpose, in the present 80 construction the feeding plate is formed so that a portion of its surface over which the cap strip is fed and which is engaged by the pawl is inclined away from the pawl. More- 85 over in order to insure a positive engagement between the pawl and the cap strip during the initial stages of the feeding operation, it is desirable not to so incline the portion of the feeding plate initially engaged, but, rather, to incline the same toward the feed- 90 ing pawl.

95 In the construction shown in the accompa- 100 nying drawings it will be noted that at the lower end 26 the surface of the plate, which is the portion of the plate first engaged by the pawl, is inclined rearwardly or toward the feeding pawl, but substantially at a point 27 the plate surface is inclined in a reverse direction or away from the pawl. This inclination continues to a point 28 which is the limit of 105 the travel of the pawl. When the trigger is retracted the pawl engages the cap at substantially the lower end of the anvil extension or feeding plate and for a suitable distance, ordinarily about one-eighth of an inch 110

of feeding travel, the plate is inclined toward the pawl which insures a positive engagement between the pawl toe 16' and the cap strip. During the continuation of the travel of the pawl upwardly it moves over the reversely inclined portion of the feeding plate surface and, consequently, although the spring 17 is compressed further and its tension gradually increases, due to the movement of the pawl pivot toward the feeding plate, the inclination of the plate surface above described makes an allowance for this increase in tension and serves to prevent the pawl from exerting too great a pressure upon the cap strip. It should further be observed that from the point 28 the plate is inclined again rearwardly so that the anvil 24 is not perpendicular, but is inclined rearwardly with respect to a perpendicular plane. This inclination is desirable for the reason that it increases the volume and 20 portion of the explosion to a certain extent.

By curving the portion of the feeding plate 24' over which the feeding pawl travels, it is possible to obtain a feeding movement of the cap strip in excess of the pawl movement in the same direction. In other words, the pawl travels in a curvilinear path, due to the curvature of the surface of the feeding plate between the points 26 and 28, and advances the cap strip a greater distance than if the pawl travelled in a rectilinear path between the same points. It will be understood, that it is, of course, desirable to have only a limited feeding pawl movement since extended movement compresses extremely the spring 18, and destroys in a short time the original resiliency and tension of the spring. If the movement of the pawl is limited, as is possible in a construction such as has been described without reducing the distance the strip is advanced, the spring 18 is not compressed during the latter stages of the pawl movement to an undesirable degree, and the life of the same is thus considerably protracted.

Obviously, the invention is not limited to the provision of a feeding plate having, strictly speaking, a "curved" surface over which the feeding pawl travels since most any other formation than a plane or rectilinear surface between the point of engagement 26 of the pawl with the plate 24' and the point 28 where the movement of the pawl terminates would accomplish this same result, namely of effecting a rectilinear advancement of the cap strip greater than the movement of the feeding pawl in the same direction. It should be understood, therefore, that when the term "curved" is used in the specification and claims with reference to the formation of the feeding plate surface,

it is intended to cover such equivalent construction.

I claim:

1. A device of the class described comprising a cap strip feed plate over which a strip of caps is fed, a pawl for engaging and feeding the strip, means for actuating the pawl including spring means which is placed under tension as the pawl is moved, said plate having a portion of its surface over which the pawl travels in its feeding movement inclined away from the pawl in the direction of the feed of the strip, and a portion initially engaged by the pawl not being so inclined.

2. A device of the class described comprising a cap strip feed plate over which a strip of caps is fed, a pawl for engaging and feeding the strip, means for actuating the pawl including spring means which is placed under tension as the pawl is moved, said plate having a portion of its surface over which the pawl travels in its feeding movement inclined away from the pawl in the direction of the feed of the strip, and another portion over which the strip is initially engaged by the pawl inclined toward the pawl in the direction of feed.

3. A device of the class described comprising a cap strip, a feed plate over which a strip of caps is fed, and a feed pawl adapted to be moved over a portion of the surface of said plate, that portion of the feed plate surface over which the pawl is moved in its feeding operation being of convex curvilinear formation.

4. A device of the class described comprising a cap strip feed plate over which a strip of caps is fed, a pawl for engaging and feeding the strip, means for actuating the pawl, said plate having that portion of its surface over which the pawl travels in its feeding operation of curved formation with the part over which the strip is initially engaged by the pawl being inclined toward the pawl in the direction of feed.

5. A device of the class described comprising a cap strip feed plate over which a strip of caps is fed, a pawl for engaging and feeding the strip, means for actuating the pawl, said plate having that portion of its surface over which the pawl travels in its feed operation of curved formation with the part over which the strip is initially engaged by the pawl being inclined toward the pawl in the direction of feed and the following portion over which the pawl travels inclined away from the pawl in the direction of feed of the strip.

In testimony whereof I have hereunto set my hand.

EDWARD S. PEAKE.
